UNITED STATES PATENT OFFICE.

JANG LANDSING, OF ROCKVILLE CENTER, NEW YORK, ASSIGNOR TO
GERTRUDE JENKINS KREMELBERG, OF NEW YORK, N. Y.

SYSTEM AND APPARATUS FOR FLUSHING.

SPECIFICATION forming part of Letters Patent No. 761,236, dated May 31, 1904.

Application filed March 2, 1903. Serial No. 145,681. (No model.)

To all whom it may concern:

Be it known that I, JANG LANDSING, of Rockville Center, county of Nassau, and State of New York, have invented certain new and useful Improvements in Systems and Apparatus for Flushing, of which the following is a specification, reference being had to the accompanying drawings, forming a part hereof.

This invention is concerned with the provision of a system and means whereby the service and drainage pipes of a building or dwelling may be flushed automatically and at predetermined intervals. It is well known that in houses which are closed for any considerable time the water in the service-pipes gather impurity and is rendered stagnant and poisonous thereby—a condition which when established is not always removed by simply permitting the water to run through said pipes when the house is reopened for occupancy. It is also a well-known fact that the drainage-pipes in closed houses become foul and develop bacteria if they are not thoroughly and systematically cleansed, and it is believed that the air of houses which are closed for any considerable time becomes infected with disease-breeding germs that are carried up into the house from the drainage-pipes, which have been allowed to dry while in a foul state.

The object of this invention is to provide a simple and inexpensive means which may be easily and quickly connected with the piping of the house for permitting the water in the main to flow at regular predetermined intervals through the service-pipes and to be discharged into the drainage-pipes to effect the cleansing of the entire piping system of the house automatically for any length of time.

Hitherto means have been devised for effecting automatic flushing in which the operative power is entirely independent of the water in the main, being furnished by a separate electrical device or clockwork mechanism.

In accordance with the present invention means are provided for effecting automatic flushing, which means are adapted to be operated by the water in the main.

Another object of the invention is the pro-

vision of a safety device to be employed in this system whereby when one or more waste-pipes become clogged the water may be automatically cut off from all bowls or tanks opening into said waste pipe or pipes.

The invention will be more fully described hereinafter with reference to the accompanying drawings, in which—

Figure 1 is a view in vertical section of a house with the present system applied to the plumbing therein. Fig. 2 is a similar view, the house being provided with a roof-tank. Figs. 3 and 4 are detail sectional views of the closets and closet-tanks. Fig. 5 is a plan view of the cellar-tank and its connections with the main. Fig. 6 is a view, partially in section and partially in side elevation, of the cellar-tank and its connections with the main and the sewer. Fig. 7 is a detail view of the safety device. Figs. 8 and 9 are respectively sectional and plan views of one form of closet-tank with an automatic trip-bucket mounted therein. Figs. 10 and 11 are respectively sectional and plan views of another form of closet-tanks with an automatic trip-bucket mounted therein, and Fig. 12 is a view showing a modification of the system for use in particular localities.

A tank *a* is placed in the cellar of the building in which the present system is to be installed, and said tank is preferably placed near the water-main *b* in order that operative connections may be easily made between said main and tank. These connections comprise a supply-tube *c*, provided with a valve *d* and valve-operating handle *d'* for supplying water to the tank from the main and a valve *e* and valve-operating lever *e'* in operative relation with a float *f* in said tank. The tube *c*, which empties into tank *a*, communicates with the main *b* at a point between valve *e* and the service-pipes *g*. Tank *a* is provided with a discharge or drip cock *h* in the bottom thereof and opening into a waste-pipe *h'*, connected with the main sewer. Through said cock the tank may be emptied, and the time required for a complete discharge of the water in said tank may be graduated to any desired interval. Float *f*, which rises and falls with the

water in said tank, is connected by a link *i* to one end of an oscillating bar *j*, which is pivoted on the upper edge of the tank, the other end of said bar being operatively connected 5 with valve-operating lever *e* by a link *k*. Arm *j* is preferably hollow and is provided with a quantity of mercury, whereby the movement of said arm from its horizontal position, which position said arm assumes near the mid-10dle of its stroke, is slightly accelerated to assist it over the middle point of its motion, thereby rendering the opening and closing of valve *e* more sudden than it would otherwise be. In order to render the turning of the 15 water on and off as sudden as possible, said valve *e* is formed with a straight opening *e* therethrough, which in one position of said valve is adapted to register with the openings in the main. Moreover, valve-operating lever 20 *e* is so connected with respect to float *f* that normally or when the tank is filled the opening through said valve is substantially at right angles to the main, and when the float is in its lowermost position, which will occur upon 25 the emptying of said tank, said valve *e* will be opened to its greatest extent, thus permitting a flow of water therethrough to the service-pipes *g* and also to the tank itself by way of supply-pipe *c*. As the tank is again filled 30 float *f* rises and valve-operating lever *e* is gradually moved by the connecting-links *i* and *k* and the oscillating arm *j* to close valve *e*. It will therefore be seen that valve *e* will be turned through a certain angle before reaching 35 its open position and that it will be opened and closed suddenly. As soon as said valve is closed and the water from the main to the service-pipes *g* is cut off water will flow down from said service-pipes and through pipe *c* 40 into the tank, thus further raising float *f*, which in turn moves valve-operating lever *e*. In this way after valve *e* has been closed water will still continue to flow through pipe *c* to raise float *f* and to move valve *e* to its 45 initial position. It will be understood, however, that inasmuch as the area of the service-pipes *g* will differ in different cases it will be necessary to determine the precise connections between float *f* and valve *e* separately for each particular case.

The pipes *g* represent the usual service-pipes for conducting water from the main to different parts of the house where it is consumed for various purposes. These pipes *g* 55 will generally terminate either in a faucet *l*, which empties into a bowl *m*, or in a tube emptying into a flushing-tank *n*. In accordance with the system of flushing to which this invention relates when the house is closed 60 for any considerable time the ends of the service-pipes *g* are opened and perforated plugs *o* are inserted therein, the perforations in said plugs being of different areas which are inversely proportionate to the force or head of 65 the water in the ends of the pipes in which

they are inserted. In this way the same amount of water will flow out through the ends of each pipe in a given time, although the force or head of the water in each pipe's end will vary with the height of that end above 70 the main. In the flushing-tanks *n* the usual mechanism, which is connected with a float therein for controlling the discharge and filling of said tanks *n*, is preferably disconnected, and a siphon *p* is preferably inserted in the 75 discharge-openings of said tanks, the height of which siphon will be determined by the quantity of water which the tank will receive during a single flushing interval. When these few simple connections have been made, the 80 system is completely installed and ready for operation. It only becomes necessary now to regulate the interval between the several flushings and the interval during which each flushing shall take place. The interval be- 85 tween the several flushings is regulated, as stated above, by the drip-cock *h*, so that a complete discharge of the tank may be made to require a period equal to the desired interval. When the drip-cock *h* has been set 90 to regulate this interval, which is the interval of complete discharge of tank *a*, valve *d* in pipe *c* may be set to regulate the interval required for filling the tank, which interval, it will be obvious, is that during which the flush- 95 ing takes place. It should be observed, how- 100 ever, that while the tank is being filled the water is escaping by drip-cock *h*, and accord- 105 ingly it would be more accurate to say that the interval of flushing is regulated by both valve *d* and cock *h* rather than by valve *d* alone, although the effect of cock *h* upon the interval for filling the tank will in most cases be negligible. Each discharge of tank *a* will 110 be followed directly by the flow of water through the main *b* up through service-pipes *g*. These service-pipes will discharge into their respective bowls *m* or flushing-tanks *n*, and in the latter case the flushing-tanks be- 115 coming filled above the tops of their respec- 120 tive siphons *p* will discharge into the closets *g* below. In this way the service and waste pipes are regularly and automatically cleansed by mechanism which is both simple and inex- 125 pensive.

In some cases it may be preferable to provide a roof-tank *a'*, into which the water from the main *b* and valve *e*, controlled by tank *a*, which may also be placed upon the roof, may be directly discharged, and from this roof- 120 tank *a'* siphon-discharge pipe is connected with the service-pipes *g*, as illustrated in Fig. 2. Among the cases in which such an arrange- 125 ment is desirable are those in which the head of the water in the main is either too great or too small or where it is variable, so that in order to secure a uniform head of water of the proper strength for the purposes of flush- 130 ing in the manner hereinbefore described some such means should be provided.

It should be noted that in some cities there is a large consumption of water at certain times during the day and in many circumstances during the entire day, which consumption so reduces the force of the water in the main that it is not sufficient to cause a flow of water to the upper stories of a house. In such cases a large tank *r*, Fig. 12, similar to tank *a*, is provided in the top of the house in which the system is to be installed, which tank is of such capacity as to provide a quantity of water sufficient for flushing during the intervals when the force of the water in the main is reduced. The main *b* will be extended to the roof and near said tank *r*, and the same attachments will be made between the main and tank *r* as were made between the main and cellar-tank *a*, already described. The discharge-pipe of tank *r*, however, is not provided with a discharge valve and cock, as in tank *a*, but opens freely into pipe *s*, which conducts water from tank *r* to tank *a* in the cellar, pipe *s* in all respects answering the purposes of the main in the first case. Cellar-tank *a* in this case is identical with tank *a* which has already been described, and the same connections are made between present cellar-tank *a* and pipe *s* as were made in the first case between main *b* and tank *a*. It will be obvious, therefore, that the quantity of water in tank *r* may be so regulated that it will be discharged or emptied at some time during the night, when the force of the water in the main is sufficient to fill said tank, and it will also be obvious that the force of the water in said tank will operate cellar-tank *a* in the same manner as the force of the water in the main would operate the same and that the cellar-tank *a* will thereby be regularly filled and discharged and the flushing of the service and draining pipes effected, as has been described hereinbefore.

As was explained above, when the system is installed the mechanism ordinarily controlling the discharge and filling of the flushing-tanks *n* is disconnected and siphons *p* are inserted in the discharge-openings of said tanks. In Figs. 8 to 11, inclusive, additional mechanism is illustrated which, if desired, may be attached to the flushing-tanks *n* in order to provide for the proper flushing of these tanks and the closets connected therewith. Such mechanism comprises a trip-bucket *n'*, pivoted upon a rod *n*² and having suitable connections with the usual trip-beam *n*³. Before describing the operative connections between each trip-bucket and the trip-beam it should be observed that there are in general two forms of closet-tanks, one type of which, as illustrated in Figs. 8 and 9, is provided with a siphon-discharge and the other type of which, as illustrated in Figs. 10 and 11, is provided with the ordinary valve-discharge. In either case upon the installation of the system these flushing-tanks are each provided with a trip-

bucket having secured thereto an arm or rod, as *n*², upon the end of which is pivoted a short catch-pin *n*⁵. Each trip-bucket *n'* is mounted so as to be directly underneath the corresponding supply-cock *n*⁶, the floats ordinarily controlling the valve in said supply-cock having been previously disconnected. Each trip-bucket *n'* is provided with a small opening *n*⁷ in the bottom thereof, which is normally closed by the end of a curved rod *n*⁸, secured to the side of the tank *n*. In the case of a tank having a siphon-discharge the float therein is connected by suitable chain to the end of the trip-bucket. In the case of a tank having a simple valve-discharge the float is connected to one arm of a bell-crank lever *n*⁹, pivoted upon a bracket *n*¹⁰, the other arm of the bell-crank lever having a notch in which a pin *n*¹¹ on the trip-beam may rest while the tank *n* is being emptied, and a spring *n*¹² being provided to move said lever upon said pin at the beginning of the discharge. The discharge and filling of these flushing-tanks *n* when the trip-buckets are employed instead of the siphons, as has been heretofore described, will take place as follows: Assuming the tanks to be filled with water, as indicated in Figs. 8 and 10, water will commence to flow from the supply-cock *n*⁶ during a flushing interval into the trip-bucket *n'*. When the weight of the water in the trip-bucket is sufficient, it will cause the bucket to descend and the trip-beam to be actuated to open the outlet of the tank, and the contents thereof will be discharged. In the case of the siphon-discharge the trip-beam returns at once to its original position, thereby insuring the immediate filling of the tank as soon as a complete discharge has been effected. In case of the valve-discharge, as soon as the float has descended, it will cause the bell-crank lever *n*⁹ to become disengaged from the pin *n*¹¹, whereby the trip-beam will return to its original position and the tank will be filled. Finally, the water in the trip-bucket having been partially or wholly discharged through the opening in the bottom thereof, said bucket will return to its original position, being in readiness to effect the actuation of the trip-beam at the next flushing interval. The tanks *n* may be filled in the first instance by opening the supply-cock *n*⁶ to its full extent or in any other suitable manner.

In order to provide against any serious consequences which might be occasioned by the clogging of the main sewer or any of the waste-pipes, a safety device (see especially Fig. 7) is provided and may be attached to any and all faucets or discharge-openings in the system. Said safety device comprises a float *t*, having an arm *u* secured thereto, which arm is loosely fitted in a bearing *v*. This safety device is mounted with respect to a discharge-opening or faucet in such a way that the float will rest normally in the bowl *z*.

or tank into which said faucet discharges, while the rod mounted upon said float will be in a vertical line with the opening in said faucet. The upper end of said rod is provided with a plug or stop-ball *w*, which upon the upward movement of said rod is adapted to be jammed into the opening of a perforated plug *o*, which, as before described, is provided upon each of the faucets, said opening being 5 preferably conical in shape. As will be obvious, when an obstruction occurs in the waste-pipe to prevent the proper discharge of the water from the bowl the float *t* will be raised by the water therein and the stop-ball *w* will be jammed into the opening of plug *o*, thereby shutting off the further flow of water into the bowl. In the case of the flushing-tanks *n* the rod *u* instead of being provided with a stop-ball or plug, may be attached to the rod ordinarily carrying the float in said tank, (see Fig. 3,) whereby when the closet becomes clogged the last-mentioned rod will be raised and the supply-cock for the flushing-tank will be closed.

25 I claim as my invention—

1. The combination with a water-supply pipe provided with a valve to control the flow therethrough, of a tank, a pipe leading from the supply-pipe to the tank and also controlled 30 from said valve, means controlled by the rise and fall of water in the tank to close and open the valve and thereby permit a flow through both of said pipes when the tank is empty, and shut off the flow through both when the 35 tank is filled, and means for discharging the contents of the tank.

2. The combination with a water-supply pipe provided with a valve to control the flow therethrough, of a tank provided with means 40 for discharging its contents, a float in the tank, connected with the valve and adapted when raised to close the said valve and when lowered to open it, and a pipe connected to the supply-pipe beyond its valve, and opening 45 into it.

3. The combination with a water-supply

pipe provided with a valve to control the flow therethrough, of a tank, a float in the tank connected to the valve to close it when raised and open it when lowered, and a branch pipe 50 leading from the supply-pipe beyond said valve and discharging into the tank; said tank having an outlet of less area than the said branch pipe to permit the tank to be filled and slowly emptied.

4. The combination with a water-supply pipe leading to a part to be flushed and there terminating in a perforated plug, a valve in the pipe to control the flow therethrough, of a tank, a pipe leading from the supply-pipe 60 to the tank and controlled from said valve, means controlled by the rise and fall of the water in the tank to close and open the valve.

5. The combination with a water-supply system in a building or dwelling, which system comprises a water-main and service-pipes leading to different parts of said building or dwelling and having their ends open for the passage of water therethrough, of a valve in said main controlling the flow of water through 70 said main, a tank in the upper part of the building or dwelling provided with supply and discharge pipes and adapted to receive a supply of water when said valve is open, means controlled by the water in the tank for opening and closing said valve, a pipe leading from the discharge of said tank to said service-pipes, a valve in said pipe, a second tank in the lower part of said building or dwelling provided with supply and discharge pipes and 75 adapted to receive a supply of water when said second-named valve is opened, and means controlled by the water in said second-named tank for opening and closing said second-named valve.

85 This specification signed and witnessed this 11th day of February, 1903.

JANG LANDSING.
